DESIGN FOR A TABLE LIGHTER

Herman G. Treiss, Brooklyn, N. Y., assignor to
H. Negbaur & Co., New York, N. Y., a copartnership composed of Harry Negbaur and Dorothy B. Negbaur

Application August 16, 1946, Serial No. 132,590

Term of patent 7 years

(Cl. D48—27)

To all whom it may concern:

Be it known that I, Herman G. Treiss, a citizen of the United States of America and a resident of Brooklyn, in the county of Kings and State of New York, have invented a new, original, and ornamental Design for a Table Lighter, of which the following is a specification, reference being had to the accompanying drawings, forming a part thereof.

In these drawings:

Figures 2 and 3 are side and end elevational views of the same, respectively.

I claim:

The ornamental design for a table lighter, as shown.

HERMAN G. TREISS.
